UNITED STATES PATENT OFFICE.

BERT SELFRIDGE, OF BUTTE, MONTANA.

PACKING DEVICE FOR DRILL-RODS OR THE LIKE.

SPECIFICATION forming part of Letters Patent No. 723,740, dated March 24, 1903.

Application filed October 11, 1902. Serial No. 126,943. (No model.)

To all whom it may concern:

Be it known that I, BERT SELFRIDGE, a citizen of the United States, and a resident of Butte, in the county of Silverbow and State 5 of Montana, have invented certain new and useful Improvements in Packing Devices for Drill-Rods or the Like, of which the following is a full, clear, and exact description.

The object of my invention is to provide for 10 the piston-rods of rock-drills more efficient guide and packing devices.

The improvements are specially applicable to rock-drilling machines such as the Rand or the Ingersoll-Sergeant machines, in which the 15 pistons, the piston-rod, and the drill-chuck are integral.

My invention consists of the novel features hereinafter particularly described and claimed.

20 Reference is to be had to the accompanying drawings, forming a part of this specification, in which similar characters of reference indicate corresponding parts in all the figures.

Figure 1 is a side elevation, partly in section, showing my improvements applied. 25 Fig. 2 is a similar view showing my improvements in a slightly-different form. Fig. 3 shows in side elevation and in plan a bonnet employed in carrying out my improvements 30 when constructed as shown in Fig. 1. Fig. 4 is a plan view of a yoke employed in connection with said bonnet. Fig. 5 shows in plan and side elevation my improved split sleeve to form a guide for the piston-rod. 35 Fig. 6 shows in plan and in elevation a split gland employed in carrying out my invention, and Fig. 7 shows in plan and side elevation a bonnet of the form employed in the arrangement shown in Fig. 2.

40 It is the custom in drilling-machines such as the Rand and Ingersoll-Sergeant to form the pistons A, piston-rod B, and drill-chuck C integrally, and this fact dictated the details employed in the practical embodiment 45 of my improvements.

Referring more particularly to the construction shown in Figs. 1, 3, 4, 5, and 6, a longitudinally-split bonnet D is provided, having its inner end d reduced to project 50 partly into the cylinder E of the drilling-machine, the shoulders d' at the base of said reduced end d coming to a bearing against the

end of the said cylinder. Within the bonnet D is a longitudinally-split sleeve F, having an external annular flange f, fitting a corresponding groove d² in the bonnet D, whereby said sleeve will embrace and guide the piston-rod B. It will be observed that the piston-rod is of less diameter than the pistons A and chuck C. Hence the split form of the 60 bonnet D and sleeve F. A yoke G surrounds the bonnet D by a taper fit, the opposed surfaces d³g being oppositely tapered, as shown, and said yoke has opposite ears g', through which pass the bolts H, having nuts h for 65 drawing the yoke G to place. The bolts H pass also through the ears or lugs a on the adjacent end of the cylinder E and are of sufficient length in practice to secure the rear cylinder-head. (Not shown.) The outer 70 end of the bonnet D has a stuffing-box comprising a longitudinally-split gland I, a nut J, and check-nut K, the said gland being spaced from the split sleeve F and the intervening space having packing L, surrounding 75 the piston-rod. The nuts J K have engagement with exterior threads d⁴ on the bonnet D, and the outer end of the nut J has an internal annular flange k, that bears against a shoulder i on the gland I to draw said gland 80 to place. The yoke G and the nuts J K are large enough to slip over the pistons A when my improvements are to be applied to or removed from the machine, while the sleeve F, 85 bonnet D, and gland I are of less internal diameter, but being split longitudinally may be separated laterally when being applied or removed.

The only parts of my improvement subjected to wear are the sleeve F and gland I, 90 and they may be renewed at small cost and with a minimum loss of time and labor. Thus the guiding and packing devices may be maintained in perfect condition, which is very important, owing to the high pressure at which 95 compressed air is employed in the operation of drilling-machines.

The arrangement shown in Figs. 2 and 7 is very similar to that already described, the only difference being that the yoke G is omitted, the bonnet D' being formed with integral lugs D² for receiving directly the securing-bolts H and nuts h and with mating lugs d⁵ d⁵ on the halves of the bonnet for receiv-

ing the bolts D³, that clamp said halves together around the split sleeve F'.

Having thus described my invention, I claim as new and desire to secure by Letters 5 Patent—

1. The herein-described devices for guiding and packing the rod of a drilling or other machine, comprising a bonnet attachable to the cylinder of the machine, a longitudinally-split sleeve in said bonnet for guiding the rod, and a stuffing-box on the bonnet, said stuffing-box including a longitudinally-split gland.
2. The combination with the cylinder and piston-rod of a drilling or other machine, of an attachment comprising a bonnet, a sleeve in the bonnet forming a guide for the said piston-rod, and a stuffing-box on the bonnet, said stuffing-box including a gland, the inner end of the gland being spaced from the outer end of the sleeve thereby forming a longitudinal space for packing between the said sleeve and gland.
3. The herein-described devices for guiding and packing the piston-rod of a drilling-machine, comprising a longitudinally-split bonnet, means for attaching the bonnet to the cylinder of the drilling-machine, a longitudinally-split sleeve in the bonnet and forming along its length a surface to closely embrace the piston, and a stuffing-box on the bonnet, said stuffing-box having a longitudinally-split gland, the inner end of the bonnet being spaced from the outer end of the sleeve to receive packing between them.
4. The herein-described devices for guid-

ing and packing the piston-rod of a drilling-machine, comprising a longitudinally-split bonnet, means for attaching the bonnet to the cylinder of the drilling-machine, a longitudinally-split sleeve in the bonnet, and a stuffing-box on the bonnet, said stuffing-box having a longitudinally-split gland, the said split sleeve having an external annular flange, and the said bonnet having a corresponding 45 groove receiving said flange.

5. The herein-described devices for guiding and packing the piston-rod of a drilling-machine, comprising a longitudinally-split bonnet, a yoke encircling the bonnet and 50 adapted for engagement by rods on the cylinder of the machine, a longitudinally-split sleeve in the bonnet, and a stuffing-box on the bonnet, the gland of the stuffing-box being split longitudinally.

6. The herein-described devices for guiding and packing the piston-rod of a drilling-machine, comprising a longitudinally-split bonnet, a yoke encircling the bonnet and adapted for engagement by rods on the cylinder of the machine, the said yoke having a tapered fit on the bonnet, a longitudinally-split sleeve in the bonnet, and a stuffing-box on the bonnet, the gland of the stuffing-box being split longitudinally.

In testimony whereof I have signed my name to this specification in the presence of two subscribing witnesses.

BERT SELFRIDGE.
